UNITED STATES PATENT OFFICE.

SAMUEL COHEN, OF ST. PAUL, MINNESOTA.

SLEEVE LINING.

Application filed November 29, 1922. Serial No. 603,967.

To all whom it may concern:

Be it known that SAMUEL COHEN, a citizen of the United States, residing at 1147 Lincoln Avenue, St. Paul, in the county of 5 Ramsey and State of Minnesota, has invented certain new and useful Improvements in Sleeve Linings, of which the following is a specification.

My invention relates to sleeves, and more 10 particularly to sleeves of easily stretched material such as leather.

The object of my invention is to prevent the stretching of sleeves formed of leather whereby the shape of the sleeves 15 at the elbows may be maintained even after long continued use and in addition the life of the sleeves is greatly prolonged.

Another object of my invention is to construct a sleeve wherein the reinforcing 20 means can be applied together with a portion of the sleeve which it is desired to reinforce, thus effecting a saving of time and labor.

A still further object of my invention is 25 to so attach the non-stretching reinforcing means that there shall be a slight giving or flexing of the leather of the sleeve on movement of the arm in order to permit the leather to be kept soft and pliable and to 30 prolong its life.

Heretofore the leather sleeves of coats that had been worn for any considerable 35 time became baggy at the elbow. This occurred because at each bending of the elbow the leather was stretched and after repeated stretchings the leather lost its elasticity and the material became permanently stretched. Not only is the above true, but where leather 40 is stretched to its utmost as when the arm is bent in leaning on a counter, the chances of abrasion and wear by friction are great, and in the portion of the sleeve in proximity to the elbow, by reason of this exterior and interior abrasion, the sleeve quickly wears 45 out.

It is to overcome this difficulty existing in the present-day leather garments that this invention was conceived. In one form of my invention I provide the leather sleeve 50 with a lining strip of non-stretching material which extends over approximately one-half of the circumference of the interior

of the sleeve and at the back thereof. The strip is of such a length that it extends from just above the wrist to a short distance above 55 the elbow. The lining strip is firmly fastened to the interior of the leather sleeve by a plurality of rows of stitching which hold it firmly in place. In another modification the lining may be extended from 60 the armpit to the wrist.

In the drawings.

Figure 1 is a perspective view showing the position of the lining in the sleeve, such lining being indicated in dotted lines; 65

Fig. 2 is a perspective view of a sleeve turned wrong side out, showing the lining in place;

Fig. 3 is a cross section taken on the line 3-3 of Fig. 2; 70

Fig. 4 is a detail of the two-part leather sleeve turned inside out, with portions of the lining and the lower part of the sleeve turned back to show the form of stitching;

Fig. 5 is a longitudinal cross-sectional 75 view of my sleeve;

Fig. 6 is a bottom plan of a sleeve turned inside out with part of the lining turned away showing the leather behind the lining.

In the drawings I have illustrated a 80 leather coat 1, having a leather sleeve 2 attached thereto in the usual manner. The leather sleeve is formed of two parts, each of which forms substantially one-half of the sleeve. The front part 3 is made slightly 85 broader than the back part 4. The front part 3 of the sleeves has turned under edges 5 to which are sewed the edges 6 of the back part 4 of the sleeve.

The back part 4 of the sleeve is divided 90 into an upper part 7 and a lower part 8. The upper part 7 extends downward to a point above the elbow and has a turned up end 9. The lower part 8 is adapted to fit under the turned up end 9. The position 95 of the lower part 8 with respect to the upper part 7 can be plainly seen by reference to Fig. 4 which illustrates a sleeve turned inside out.

The folded over edge 5 of the front part 100 3 of the sleeve is sewed to the edge of the upper part 7 by a double row of stitching 11. The lower part 8 of the sleeve is sewed to the front part 3 by means of a continua-

tion of the same double row of stitching. This double row of stitching in the lower part of the sleeve not only holds the lower part 8 to the upper part 7, but also holds a strip of non-stretching material 12, such as any of the kinds of non-stretching cloth on the market or any other desired material, to the lower part 8 of the sleeve. The non-stretching material 12 is slightly larger than the adjacent sleeve portion to which it is secured so as to allow a certain optimum degree of stretching to keep the leather "live" and prolong its life, but the material 12 is so adjusted as to prevent the leather from being subjected to any excessive or deleterious strain. This double row of stitching 11 holds the non-stretching material 12 firmly to the lower part 8 of the sleeve which is ordinarily subjected to considerable stretching strain in moving the arm.

A double row of stitching 13 holds the non-stretching material 12 to the lower part 8 of the sleeve at the top and the stitches pass through the up-turned edge 9 of the upper part 7 of the sleeve, binding the whole together. At the bottom of the lower part 8 of the sleeve a row of stitching 14 holds the non-stretching material 12 to the lower part 8.

In another modification such as is shown in Figs. 5 and 6, I have shown the leather sleeve as comprising the usual front part 3, and the back part is formed of a plurality of pieces 20, which I have shown as three in number though there may be a greater or less number of them. The non-stretching material 12 extends all the way from the armpit to the wrist. Since there is considerable strain at the armpit, the fact that the non-stretching lining material 12 is sewed with the leather to the body of the sleeve by a double row of stitching 21, tends to make a much stronger construction. A large portion of the strain when bending the arm comes on the seam at the arm-hole, but the perforations of the needle in sewing the sleeve to the body will not weaken the structure at all and the leather will be prevented from tearing.

The fact that the back part or "under sleeve" is generally formed of two or more pieces which must be sewn together, renders this modification extremely useful since the juncture of these leather pieces is sewed to the lining by double rows of stitching indicated at 22.

By reason of the plurality of rows of stitching fastening the edges of the strip of non-stretching material to the leather of the sleeve, the leather cannot stretch. This prevents eventual loss of elasticity and consequent bagginess common to leather sleeves of garments after continued wear. The

reinforcement inside the sleeve relieves the leather of the friction of the arm against it and leaves the leather free from tension, thereby increasing the life of the sleeve as well as preventing bagginess. But by reason of the slight stretch of the leather permitted by the lining, since the lining is adjusted to allow a slight play of the leather, its life and pliability is retained.

The construction of the sleeve with an upper and lower back part permits the non-stretching material 12 to be applied to the lower back part and the whole sewed together in one operation, thus effecting a great saving of time, and, moreover, giving a very strong construction.

While I have shown and described the preferred embodiment of my invention, I wish it to be understood that I do not confine myself to the precise details of construction herein set forth; by way of illustration, as it is apparent that many changes and variations may be made therein, by those skilled in the art, without departing from the spirit of the invention, or exceeding the scope of the appended claims.

I claim:

1. In a leather sleeve the combination of a front part and a back part secured thereto by suitable rows of stitching, a lining strip arranged adjacent to the inner surface of the back part of the sleeve and secured by said rows of stitching thereto, said lining strip consisting of non-elastic easily flexed material and being slightly larger within said rows of stitching than the rear part of the sleeve to permit a slight stretching of the leather of the rear part before the lining strip comes into active play to resist excessive or deleterious strain on said rear part.

2. The combination in a sleeve having a rear part formed of leather, a non-elastic flexible lining secured adjacent to said rear part with suitable rows of stitching, said lining being slightly larger, within said stitching, than the rear part of the sleeve, so as to permit a slight stretching of the leather before the lining is brought into play.

3. The combination of a sleeve of leather with a non-stretchable flexible lining in proximity to the elbow of the sleeve and securely fastened about its edges to the sleeve, said lining being of a size greater than the normal size of the corresponding portion of the sleeve but lesser than the optimum stretchable limit of said corresponding sleeve portion, so as to limit the stretching of the same.

4. The combination in a sleeve having a leather back portion, a flexible non-stretchable lining strip stitched about its edges to the back portion, said lining strip being slightly wider between opposite stitched edges thereof than the corresponding part of

the back portion, so as to permit a slight stretching of said corresponding part before the lining strip is brought into play.

5. The combination in a sleeve having a back part formed of a number of stretchable pieces secured together by rows of stitching, a flexible non-stretchable lining strip extending from the wrist to the armpit of the sleeve and secured to the back part

by the said rows of stitching, the sectional portions of said lining covering said pieces being slightly larger, respectively, than the pieces, so as to permit the pieces to be stretched to the limit allowed by the lining.

In testimony whereof he has affixed his **15** signature.

SAMUEL COHEN.
